(57) **CLAIM**

The ornamental design for a hood shield with light, as shown and described.

DESCRIPTION

FIG. 1 is a a front, left, and top perspective view of a hood shield with light, showing my new design;

FIG. 2 is a rear, bottom perspective view thereof;

FIG. 3 is a right and front perspective view thereof;

FIG. 4 is a rear, top perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is an enlarged view of detail “11” identified in FIG. 1;

FIG. 12 is an enlarged view of detail “12” identified in FIG. 2; and,

FIG. 13 is an enlarged view of detail “13” identified in FIG. 4.

The dashed broken lines in the figures illustrate portions of the hood shield with light that form no part of the claimed design. The dash dot dash broken lines in FIGS. 1, 2, 4, 11, 12 and 13 are for the purpose of illustrating the enlarged view indicators and form no part of the claimed design.

1 Claim, 13 Drawing Sheets
